COMPARTMENTED PLATE

Ali R. Caner, Batavia, Ill., assignor to
American Can Company

Filed Oct. 1, 1974, Ser. No. 511,399

Term of patent 14 years

Int. Cl. D7—01

U.S. Cl. D7—1

FIG. 1

FIG. 2

FIG. 3

FIG. 4

FIG. 5

FIG. 1 is a top plan view of a compartmented plate showing my new design;

FIG. 2 is a front elevational view of the compartmented plate of FIG. 1;

FIG. 3 is a rear elevational view of the compartmented plate of FIG. 1;

FIG. 4 is a bottom plan view of the compartmented plate of FIG. 1; and

FIG. 5 is an enlarged cross-sectional view taken along line 5-5 of FIG. 1.

My design is characterized by the shape and configuration of the plate, which is basically square with convex sides and corners when viewed from above or below; the sides being inclined downwardly and inwardly to a square base, with convex sides and corners, the base having a T-shaped ridge dividing it into three planar sections, including a larger section occupying more than one-half of the area of the base, the ridge including an elongated, flat, concave-convex top with the concave side thereof on the side of the larger section, and downwardly and outwardly inclined straight sides, the ends of the top of the T flow-

ing through concave arcs into the centers of two opposing sides of the plate; the bottom of the plate being a mirror image of the top of the plate displaying convex projections extending from each corner along each adjacent side, one convex projection being continuous along the outer side edge of the plate beneath the larger planar section of the base.

I claim:

The ornamental design for a compartmented plate, substantially as shown and described.
